CLAIM

The ornamental design for a cradle for communications headset, as shown and described.

DESCRIPTION

FIG. 1 is a front right perspective view of a cradle for a communications headset, the broken line drawing of the communications headset resting in the cradle is for illustrative purposes only and forms no part of the claimed design.

FIG. 2 is a front right perspective view of the cradle;

FIG. 3 is a rear right perspective view of the cradle;

FIG. 4 is a front elevational view of the cradle;

FIG. 5 is a right side elevational view of the cradle, the left side elevational view of the cradle being a mirror image thereof;

FIG. 6 is a rear elevational view of the cradle;

FIG. 7 is a top plan view of the cradle; and,

FIG. 8 is a bottom plan view of the cradle.

The broken lines in FIG. 1 is for illustrative purposes only and forms no part of the claimed design.
